SPACING MECHANISM FOR TYPE-BAR-MAKING MACHINES.

1,200,228.

Specification of Letters Patent.

Patented Oct. 3, 1916.

Application filed September 3, 1914. Serial No. 860,096.

To all whom it may concern:

Be it known that we, DAVID PETRI-PALMEDO and EDWARD F. GODDARD, citizens of the United States, and residents, respectively, of Bridgeport, in the county of Fairfield and State of Connecticut, and Stratford, in the county of Fairfield and State of Connecticut, have invented a certain new and useful Improvement in Spacing Mechanism for Type-Bar-Making Machines, of which the following is a full, clear, and exact description.

This invention relates particularly to the kind of circulating matrix type bar making machines in which the justification of the matrix line is effected by means of expanding wedge space bands placed between the words. In operating machines of this sort many short lines are set. It is customary, in operating machines of this character as they have heretofore been constructed, to quad out each short line so that said line composed of matrices, quads and expanding space bands, shall be of justifiable length, *i. e.* can be spread to standard length by expanding the space bands therein.

The addition of the quads to the short lines takes considerable time, and very materially reduces the output of such machines, and is therefore objectionable.

It has been proposed to use at the rear end of the matrix line to clamp the same for coöperation with the mold, a spring actuated movable end clamp which will close so much of the mold slot as is not covered by the short line, and to thereby render the use of quads unnecessary. Such an end clamp has been used successfully in machines which did not use expanding space bands for justifying lines. Attempts have also been made to use such an end clamp in machines in which the wedge space bands were used, but this heretofore has not been attended with satisfactory results, because when the space bands in a short line were expanded by the mechanism provided for that purpose the movable parts of the space bands are driven up so far that the parts of the space bands in the line become abnormally and undesirably wide.

The object of this invention is to produce, for presentation to the mold, in a machine which employs the spring actuated mold-closing end-clamp, and which also employs

expanding space bands, a short line having 55 normal spaces between the words. By "normal" spaces are meant spaces of the required width to cause the line to present a good appearance,—spaces neither too wide nor too narrow. To do that, means are provided by which the spring induced upward movement of the justifier hammer which expands the space bands is arrested after it has moved up such a distance as to cause the space bands between the matrices to become of ideal, or, as commonly stated, of 60 normal width. The means by which this is accomplished automatically or at will, when the lines are short, constitutes the present invention which is shown in the drawing, 65 and hereinafter described and definitely pointed out in the appended claims.

In the drawing, Figure 1 is a front elevation of so much of a type bar making machine as is necessary to a complete disclosure 75 of the present invention. Fig. 2 is a side elevation of said mechanism partly sectioned in the plane indicated by line 2—2 on Fig. 1. Fig. 3 is a front elevation of a part of the detent slide and the cam plate trip mechanism adjustably secured thereto. Fig. 4 is a plan view of the mechanism shown in Fig. 3, and the adjacent mechanism adapted to be operated by said trip mechanism. Fig. 5 is a sectional plan view of the line carrier. 80 Fig. 6 is a side elevation of the elevator showing the normal position of certain parts thereon when the elevator is supporting a full line. Fig. 7 is a side elevation of the same mechanism showing the same parts in 85 the position they will occupy when the elevator contains a short line. This figure also shows a part of the justifier hammer in section. Fig. 8 is a right end view of certain mechanism associated with the rock shaft. 90 95

In machines of this general character and particularly in the machine for which this invention in the precise form shown was designed for use, the unjustified matrix line, *i. e.* lines composed of matrices M and wedge space bands S are assembled on assembling rails R. The middle portions of these rails are broken away as shown in Fig. 1, but those familiar with this art will understand that they are long enough to hold the longest 100 matrix line upon which the machine is adapted to cast a slug.

A detent *d* which is connected to a detent

slide D is in such position that the foremost matrix in the line engages it; and therefore as the growing matrix line is moved along the assembling rails by the familiar star 5 packer P, the detent slide will move a like distance. After the line has been assembled, it is pushed onto the first elevator E by a line carrier C. The line carrier is a slide having an arm C¹ adapted to engage the 10 last matrix added to the line. When this line carrier is moved to the left by known mechanism or any suitable mechanism, it pushes the unjustified matrix line, made up of matrices and wedge space bands, onto the 15 elevator E. The elevator then descends, carrying the matrix line between a fixed abutment A and a movable end clamp L. This end clamp is a horizontally movable slide, whose rear face is in the same vertical plane 20 as the rear faces of the assembled matrices. When the matrix line, supported by the elevator, is clamped between the abutment A and the movable end clamp L, the justifier hammer H is moved up by the action of a 25 spring (not shown) and thereby the depending members s of the wedge space bands S are moved up equal distances, thereby expanding the space bands and spreading the line, which, as it spreads, thrusts to the 30 right against the movable end clamp.

All of the parts above referred to and suitable mechanism for actuating them are so well understood in this art that it has not been thought necessary to show them to 35 any greater extent than they are shown in the drawing, or described them any more completely than they are herein described. The elevator referred to is the one which is known in this art as the first elevator; and 40 is to be found associated with suitable actuating mechanism in all linotype machines. The present invention is wholly independent of any particular mechanism for moving said elevator.

45 The line clamping mechanism which may be employed to clamp the line on the elevator; when the latter has been lowered is fully described in the application of Palmedo and Goddard, filed August 5, 1914, Serial No. 50 855,259, which application also shows and describes the means by which the justifier hammer is actuated by a spring in the space band expanding direction. Suitable mechanism for actuating the line carrier is shown 55 and described in the Le Boeuf Patent No. 1,061,388; and the mechanism by which the space bands may be released, and particularly the means by which the depression of a space key causes one revolution of the shaft 60 which carries the cam are shown and described in the Le Boeuf Patent No. 1,082,275, and in an application of Palmedo filed June 4, 1914, Serial No. 842,859.

The elevator E carries a horizontal rock 65 shaft E² to which is secured a dog E³, which

normally occupies the position shown in Fig. 6, where it will not interfere with the complete upward movement of the justifier hammer H. This dog may, however, be moved to the position shown in Fig. 7, where 70 it will be in the path of a part which is connected with and moves with the justifier hammer and will therefore limit the spring-induced upward movement thereof. The particular thing carried by the justifier 75 hammer which comes in contact with said dog is a buffer plunger H¹ which is under the influence of a spring H² which yieldingly resists its downward movement relative to said hammer, thus preventing any shock 80 to the mechanism. This plunger, however, will eventually move down until its head engages the bracket H⁴ which carries it, and then further upward movement of the hammer is definitely stopped.

85 The dog E³ is normally held in the retracted position by the spring plunger E⁴ carried by the upward extension of said dog, which plunger presses against a surface E⁵ on the elevator. This rock shaft also carries 90 an arm E⁶ which overhangs the projecting end of the stop rod G when said end projects to the left beyond the adjacent one of the two bearings F¹ carried by the fixed framework of the machine in which said rod is 95 slidably mounted. The end of this rod does not normally project into the path of the arm E⁶, but it may be made to so project by mechanism to be described, either manually, or automatically, when the line on the 100 elevator is a short line. When it does project and when the elevator goes down to carry the matrix line thereon into the casting position between the abutment A and the spring actuated end clamp L, the arm 105 E⁶ will strike the projecting end of said rod, and thereby rock the rock shaft E² so as to carry the end of the dog E³ into the path of the buffer plunger H² before referred to 110 carried by the justifier hammer. When, now, the justifier hammer, actuated by its spring, goes up, it can only go far enough to partly expand the wedge space bands S, thereby causing them to become of such 115 width in the line as is required to produce what is known as normal spacing,—that is to say, so that the words will be separated to the ideal distances.

120 Mounted on the right side of the elevator is a spring actuated lever E⁸ under the influence of a spring E⁹ which acts to hold it against a pin E¹⁰ carried by the elevator. When the elevator goes down to the casting position this lever will strike the projecting end of the rod G and be swung upward until 125 it passes such rod, whereupon said lever will resume its normal position. When, now, the elevator ascends, an inclined surface E¹² on said lever will engage the end of rod G and will thereby push the same to 130

the right into its normal position in which it will be automatically held by certain latch mechanism now to be described.

At the right end of this rod G is a spring actuated lever G² which is pivoted to a fixed bracket F². The downwardly extended arm of this lever enters a notch G¹ in the rod whereby when either the rod or lever moves the other must move correspondingly. This lever is under the influence of a spring G³ which acts to so swing the lever as to move the rod to the left. The upwardly extended arm of the lever G² is normally engaged by a catch G⁴ which is likewise pivoted to the bracket F² and is under the influence of a spring G⁵ tending to hold it in the latching position shown. This catch has connected with it two arms G⁶ and G⁷. The latter is in the form of a key upon which the operator may conveniently press to swing this catch into the lever releasing direction, which will permit spring G³ to so rock lever G² that the rod G will be moved to the left. The arm G⁶ extends upward to a position where it may be engaged by certain mechanism to be presently described by which the catch G⁴ will be moved in the lever releasing direction when a short line is being moved along the assembling rails and onto the elevator. The arm G⁷ may obviously be omitted, since it is a mere convenience for the manual operation of the catch. But the operator might take hold of the catch lever itself and operate it; or he might press against the lever arm G⁶, if he so preferred. The upwardly extended arm G⁶ might also be omitted, if it was not thought desirable, or worth while to provide mechanism for automatically releasing the catch when a short line is being pushed onto the elevator. In that event the operator would have to watch and see when a short line was on the way to the elevator, and then manually trip the catch.

The line carrier C is merely a slide moving in fixed guideways and provided with an arm C' adapted to engage the rear end of the matrix line and push it along the assembling rails and onto the elevator whose matrix receiving portion at that time will, of course, be alined with the assembling rail. Any well known or suitable mechanism for moving this line carrier may be employed. Pivoted to this line carrier is a pawl lever C² whose depending arm is normally in such position that when the lower line carrier is moved to the left this pawl will engage the arm G⁶ and trip the catch G⁴. This lever is under the influence of a spring C³ tending to hold it in this position. It has an arm C⁴ which enters a notch in the plunger C⁵ which is vertically movable in a bracket C⁶ carried by said line carrier. When this plunger is moved down in opposition to spring C³ it swings the pawl C² up into a position such that it will not strike the lever G⁶. When the plunger C⁵ has been moved down and when the line carrier starts its movement to the left, and while the spring plunger is still held down, a little dog C⁷ pivoted to the bracket C⁶ will be swung by a spring plunger C⁸ into a notch C⁹ in said plunger, and thereby the plunger will be held down until the line carrier again returns to its normal position and causes said dog to engage a fixed part of the framework F⁵ and be thereby so swung as to withdraw it from the notch in the plunger. Thereupon the pawl C² will swing to its normal position shown in Fig. 1, and the plunger will be moved up to its normal position.

As before stated, a detent d on the detent slide D extends in front of the growing matrix line which is being assembled on the assembling rails, and is moved to the left with the matrix line, step by step, by the star wheel packer P distances equal to the width of the several additions of matrices and space bands to the line. A cam piece D² is adjustably fixed to the detent slide D, and moves with it to the left as the line grows. The cam piece D² projects forward from a cam carrier D³ which is slidably mounted on the detent slide D. A dog d³ is pivoted to the cam carrier and is under the influence of a spring d⁴ which acts to force said dog downward into engagement with ratchet teeth d⁵ on the detent slide D. By lifting this dog the cam carrier may be moved along the detent slide and to any desired position thereon to conform to the desired length of a justified line. The detent slide is graduated as shown so that the operator may know when the cam carrier is at the desired point on the detent slide. By the time the line has reached justifiable length, this cam piece will have slipped under a lever arm R², or, more exactly, a roller R³, and will have lifted said arm. This arm is fixed to a rock shaft R which is mounted in fixed bearings F⁶ in which said rock shaft is likewise movable endwise. On this rock shaft R is an arm R⁴ which is provided with a tongue which enters a slot R⁶ in the rock shaft R, so that when the rock shaft R rocks, the arm R⁴ will rock with it. This arm R⁴ carries a set screw R⁵ which normally bears against the head of the plunger C⁵. When therefore the line has reached justifiable length, this cam piece D² will have rocked the rock shaft R, and thereby the plunger C⁵ will have been moved down, and thereby the pawl C² will have been moved up to the position where it will not engage the arm G⁶ when the line carrier pushes said line onto the elevator. All of the described mechanism will therefore have no effect in moving the rod G to the left if the line which is carried onto the elevator by the lower line carrier is a

full or justifiable line. If, however, the line is a short line, then the cam piece D² will not engage lever R² and will not therefore rock the rock shaft, and therefore the pawl 5 C² will remain in the position shown, in which, as the line carrier is moved to the left, it will strike the arm G⁶ and thereby withdraw the catch G⁴ and allow the rod G to be moved to the left so that when the 10 elevator descends the dog E³ will be moved into the path of the ascending justifying hammer, so as to stop said hammer at the required point in the spring-induced upward movement.

15 The arm R⁴ lies between two of the bearing brackets F⁶ in which the rock shaft R is mounted, and therefore cannot partake of the endwise movements of said rock shaft, which will now be described. This rock 20 shaft is formed with gear teeth R⁷ on its lower side, which teeth engage the gear K which is under the influence of a spring K¹ tending to turn it in the direction indicated by the arrow thereon in Fig. 1,—that is to 25 say, in the direction such as will cause the rock shaft R to move to the left when permitted to so move. There is fixed to this rock shaft a sleeve R⁸ having ratchet teeth. Adjacent to this sleeve is an actuating spring 30 pawl R⁹, which is pivoted to the depending arm of a bell crank lever R¹⁰. One arm of this lever is in position to be engaged by a cam R¹¹ which makes one revolution every time the space key is actuated. The mechanism through which this cam is caused to 35 so revolve is not new and is well understood and need not therefore be described. Every time it revolves, however, it rocks the lever R¹⁰ in opposition to its spring R¹², whereby 40 the pawl R⁹ will, by engaging the ratchet teeth on the sleeve R⁸, move the rock shaft R to the right a definite distance. Adjacent to this is a dog R¹⁴ which likewise engages said ratchet teeth and prevents said 45 shaft from moving to the left. The distance which this rock shaft moves to the right every time a space band is added to the line is equal to the difference in the width of that part of the space band which 50 lies between the matrices when the space band is narrowest, (that is to say, when the depending wedge member is hanging down) and the width of the said part of the space band when it is at its widest (that is to say, 55 when the depending wedge member has been driven up to its limit). A line is of justifiable length or is a full line when it is of such length that, by expanding to the limit all of the space bands, the line will come to 60 be of standard length. Therefore, since the space bands when they are introduced into the matrix line are thinnest, this rod R is caused to move the stated distance, and thereby the arm R⁴ will be moved that much 65 nearer the cam piece on the detent slide.

Therefore this cam piece will rock the rock shaft, not when the line made up of matrices and thin space bands is of the required length, but when the line is of such length that when said space bands are fully expanded, it will be of full or justified length. If it were not for the provision of some such compensating measuring device as has been explained the justifying hammer would be prevented from expanding the space 70 bands in all lines which were not of standard length before said space bands were expanded at all; and this, of course, will not do. It is, of course, desirable to justify all lines which are justifiable in an ordinary 80 way, and to only limit the justifying mechanism of the justifying hammer when the lines being spaced are too short to be justified regularly.

It will be understood that after a line has 85 been composed the detent D' is withdrawn from in front of the line, and this permits the detent slide to be moved back to its starting point. It will be further understood that the dog R¹⁴ will be lifted out of 90 engagement with the ratchet teeth on sleeve R⁸ and thereby the rock shaft R will be moved back to its initial position by the action of the spring K'. It will be understood also that so long as full lines only are 95 composed and moved onto the elevator, the justifier hammer will be permitted to move unrestrainedly as far as is necessary to so expand the space bands that the line will be spread to standard length. But whenever the line presented to the action of the justifier hammer is a short line,—that is an unjustifiable line, then the upward spring induced movement of the justifier hammer will be automatically restrained and limited 100 so that it can only move upward far enough to expand the space bands so that they will be of normal or ideal thickness between the words. This stoppage of the justifier hammer in its mid-position will be due to the 105 engagement of the shoulder which is formed by the upper surface of the plunger H' and the shoulder formed by the lower end of the dog E³.

Having described my invention, I claim: 115

1. In a type bar making machine, the combination of means for supporting and clamping a line made up of matrices and wedge space bands, a justifier hammer for engaging the space bands and expanding 120 them, spring actuated mechanism for operating said justifier hammer in the space band expanding direction, and means which act automatically to stop the spring induced advance of the justifier hammer at a 125 predetermined mid-position when the line about to be justified is shorter than a full line of justifiable length.

2. In a type bar making machine, the combination of the first elevator having 130

- means for supporting an unjustified line made up of matrices and wedge space bands, means for clamping said line, a spring actuated justifier hammer for engaging the space bands and expanding them, and a dog carried by the first elevator and movable into and out of the path of a part which is connected to and moves with said justifier hammer.
10. 3. In a type bar making machine, the combination of the first elevator having means for supporting an unjustified line made up of matrices and wedge space bands, means for clamping said line, a spring actuated justifier hammer for engaging the space bands and expanding them, said hammer and elevator being provided respectively with two shoulders of which one is movable into and out of a position such that during the spring induced movement of the justifier hammer these two shoulders will contact and stop the movement of said justifier hammer.
4. In a type bar making machine, the combination of means for supporting and clamping a line of matrices and expanding space bands, a spring actuated justifier hammer for engaging and expanding said space bands, means for delivering a line of matrices and space bands into the embrace of said supporting and clamping means, and mechanism which, when the line which thereby has been moved into the embrace of said supporting and clamping means is shorter than a full length justifiable line, will stop the spring induced movement of said justifier hammer in a definite mid-position.
5. In a type bar making machine, the combination of means for supporting and clamping a line of matrices and expanding space bands, a justifier hammer for engaging the space bands and expanding them, spring actuated mechanism for operating said justifier hammer in the space band expanding direction, a dog which when permitted to operate will engage and stop the ascent of the justifier hammer always in the same definite mid-position, means normally holding said dog out of action, and means to cause it to move into operative position.
6. In a type bar making machine, the combination of means for supporting an unjustified line made up of matrices and wedge space bands, a line carrier for moving said unjustified line into the embrace of said line supporting means, a spring actuated justifier hammer, normally inoperative means for limiting the spring induced movement of said justifier hammer, a train of mechanism for rendering said means operative, a movable device carried by the line carrier for causing said train of mechanism to operate, and means whereby the assembling of a full line of matrices will prevent the device car-
- ried by the line carrier from operating as described.
7. In a type bar making machine, the combination of means for supporting an unjustified line made up of matrices and wedge space bands, a spring-actuated justifier hammer for engaging said space bands and expanding them, a dog movable into and out of the path of a part which is connected with and moves with said justifier hammer, a train of mechanism which includes the line carrier and a movable part carried thereby for causing said dog to move into operative position, and means, which are caused to operate by the assemblage of a justifiable line of matrices and space bands, for rendering inoperative the movable member referred to carried by the line carrier.
8. In a type bar making machine, the combination of means for supporting and clamping a line of matrices and expanding space bands, a spring actuated justifier hammer, means for delivering a line of matrices and space bands into the embrace of said supporting and clamping means, a normally inoperative dog for stopping the justifier hammer in a definite mid-position, mechanism for rendering said dog operative, which mechanism is caused to act by the assembling of a short unjustifiable line and the subsequent movement of said short line into the embrace of the line supporting and clamping means.
9. In a type bar making machine, the combination of means for supporting an unjustified line made up of matrices and wedge space bands, a spring-actuated justifier hammer for engaging the space bands and expanding them, means for limiting the spring induced movement of said justifier hammer, means for supporting a line of matrices and space bands in the required relation to the justifier hammer, a line carrier for moving an assembled line of matrices and space bands onto said supporting means, and a movable device carried by said line carrier for causing the operation of the means for limiting the spring induced movement of the justifier hammer.
10. In a type bar making machine, the combination of an elevator constructed to support a line of matrices and wedge space bands, and adapted to move down to carry said line in the position it occupies while the space bands therein are being expanded means for clamping said line, a line carrier for moving said line onto the elevator, a spring actuated justifier hammer for expanding said space bands, normally inoperative means for stopping said justifier hammer in a definite mid-position, and mechanism for rendering operative the means for so stopping said justifier hammer.
11. In a type bar making machine, the combination of an elevator constructed to

- support a line of matrices and wedge space bands and adapted to move down to carry said line to the position it occupies while the space bands therein are being expanded, means for clamping said line, a spring-actuated justifier hammer, a dog movable into and out of the path of a part which is connected with and moves with said justifier hammer, a train of mechanism by which said dog is moved into operative position, which train of mechanism includes a line carrier by which the line is moved onto said elevator, and mechanism which becomes operative when the line has reached justifiable length for rendering inoperative the train of mechanism by which the dog is moved into operative position.
12. In a type bar making machine, the combination of an elevator constructed to support a line of matrices and wedge space bands and adapted to move down to carry said line to the position it occupies while the space bands therein are being expanded, means for clamping said line, a spring actuated justifier hammer, a dog carried by said elevator and adapted to occupy an operative position in which it projects into the path of a part which is connected with and moves with said justifier hammer or an inoperative position in which it lies outside of said path, and means for controlling the position of said dog.
13. In a type bar making machine, the combination of an elevator constructed to support a line of matrices and wedge space bands and adapted to move down to carry said line to the position it occupies while the space bands therein are being expanded, means for clamping said line, a spring-actuated justifier hammer, a dog carried by said elevator and adapted to occupy an operative position in which it projects into the path of a part which is connected with and moves with said justifier hammer or an inoperative position in which it lies outside of said path, means for normally holding said dog in the inoperative position, and means for causing said dog to move into operative position.
14. In a type bar making machine, the combination of an elevator adapted to support an unjustified line of matrices and space bands while the space bands are being expanded, means for clamping said line, which elevator moves downward to carry said unjustified line into position for justifying said line, a spring actuated justifier hammer, a rock shaft carried by said elevator, a dog fixed to said rock shaft and adapted to project into the path of a part which is connected with and moves with the justifier hammer, a spring holding the same in an inoperative position, an arm fixed to said rock shaft, a stop movable into and out of the path of said arm, spring actuated mechanism for moving said stop into operative position, and a catch restraining the movement of said mechanism.
15. In a type bar making machine, the combination of an elevator adapted to support an unjustified line of matrices and space bands while the space bands are being expanded, means for clamping said line, which elevator moves downward to carry said unjustified line into position for justifying said line, a spring actuated justifier hammer, a rock shaft carried by said elevator, a dog fixed to said rock shaft and adapted to project into the path of a part which is connected with and moves with the justifier hammer, a spring holding the same in an inoperative position, an arm fixed to said rock shaft, a stop movable into and out of the path of said arm, spring actuated mechanism for moving said stop into operative position, and a catch restraining the movement of said mechanism.
16. In a type bar making machine, the combination of an elevator adapted to support an unjustified line of matrices and space bands while the space bands are being expanded means for clamping said line, which elevator moves downward to carry said unjustified line into position for justifying said line, a spring actuated justifier hammer, a rock shaft carried by said elevator, a dog fixed to said rock shaft and adapted to project into the path of a part which is connected with and moves with the justifier hammer, a spring holding the same in an inoperative position, an arm fixed to said rock shaft, a stop movable into and out of the path of said arm, spring actuated mechanism for moving said stop into operative position, a catch restraining the movement of said mechanism, a line carrier for moving an unjustified line onto the elevator, and a device carried by said line carrier for releasing said catch.
17. In a type bar making machine, the combination of an elevator adapted to support an unjustified line of matrices and space bands while the space bands are being expanded means for clamping said line, which elevator moves downward to carry said unjustified line into position for justifying said line, a spring actuated justifier hammer, a rock shaft carried by said elevator, a dog fixed to said rock shaft and adapted to project into the path of a part which is connected with and moves with the justifier hammer, a spring holding the same in an inoperative position, an arm fixed to said rock shaft, a stop movable into and out of the path of said arm, spring actuated mechanism for moving said stop into operative position, a catch restraining the movement of said mechanism, a line carrier for moving an unjustified line onto the elevator, a device carried thereby for releasing said catch, and means for moving the device carried by the line carrier into inoperative position.
18. In a type bar making machine, the

combination of an elevator adapted to support an unjustified line of matrices and space bands while the space bands are being expanded means for clamping said line, 5 which elevator moves downward to carry said unjustified line into position for justifying said line, a spring actuated justifier hammer, a rock shaft carried by said elevator, a dog fixed to said rock shaft and adapted to project into the path of a part which is connected with and moves with the justifier hammer, a spring holding the same in an inoperative position, an arm fixed to said rock shaft, a stop movable into and out of 10 the path of said arm, spring actuated mechanism for moving said stop into operative position, a catch restraining the movement of said mechanism, a line carrier for moving an unjustified line onto the elevator, a device carried thereby for releasing said catch, means for moving the device carried by the line carrier into inoperative position, a spring detent for holding said device in operative position, said detent being so located 15 that when the line carrier returns to its normal position said detent will engage a fixed part of the machine frame and be thereby moved into inoperative position.

19. In a type bar making machine, the 30 combination of a line carrier, a spring actuated pawl pivoted thereto, a plunger mounted on the line carrier and engaging said pawl, a spring actuated detent pivoted to the line carrier and engaging said plunger, a rock shaft having one arm adapted to engage said plunger, and having also a second arm, a detent slide which is movable by a growing matrix line, and a cam plate connected with said detent slide for engagement 35 with the last mentioned arm on said rock shaft.

20. In a type bar making machine, the combination of a line carrier, a pawl pivoted thereto, a plunger mounted on the line carrier and engaging said pawl, a spring actuated detent pivoted to the line carrier and engaging said plunger, a rock shaft having one arm adapted to engage said plunger and having also a second arm, a detent slide which is movable by a growing matrix line, 45 and a cam plate connected with said detent slide for engagement with the last mentioned arm on said rock shaft, said cam plate being adjustably secured to said detent slide. 50

21. In a type bar making machine, the 55 combination of a line carrier, a spring pawl pivoted thereto, a plunger mounted on the line carrier and engaging said pawl, a spring actuated detent pivoted to the line carrier for engaging said plunger, a rock 60 shaft mounted in bearings in which it is capable of moving endwise, an arm on said rock shaft having a tongue and groove connection therewith and adapted to engage said plunger, means preventing said arm 65 from moving endwise with the rock shaft, means by which the release of a space band causes a short endwise movement of said rock shaft, a detent slide adapted to be moved by the growing matrix line, a cam 70 plate fixed to said detent slide, and an arm fixed to said rock shaft and adapted to engage said cam plate.

In testimony whereof, we hereunto affix our signatures in the presence of two witnesses. 75

DAVID PETRI-PALMEDO,
EDWARD F. GODDARD.
